(57) **ABSTRACT**

A new variety of *Gentiana* L. plant (Japanese gentian) which has a color of inner side of lobes which is strong purplish blue (96C on RHS Colour Chart) and a time of flowering in mid-October.

4 Drawing Sheets

1

Botanical classification: *Gentiana* L. hybrid.

Variety denomination: 'Ashiro 29-2030'.

BACKGROUND OF THE NEW VARIETY

The present invention relates to a new and distinct variety of Japanese gentian, *Gentiana* L., which has been given the variety denomination 'Ashiro 29-2030'.

This new gentian has a color of inner side of lobes which is strong purplish blue (96C on RHS Colour Chart) and a time of flowering in mid-October. It is adapted for use as cut flowers or pot flowers.

ORIGIN OF THE VARIETY

The variety resulted from a multiple-step cross-breeding program starting from a group of unpatented varieties. The ancestor varieties were unpatented strains owned by the applicant, having the company-internal names: '17INP' which belongs to the species *Gentiana triflora*, and '26-904', '12-316-3', '17SUP', and '8-130SP6A1', which belong to the species *Gentiana scabra*. Group crosses and/or self-crosses with a single individual were performed. The program had seven steps, as shown in the map of FIG. 6, which also indicates the company-internal names of the intermediary, unpatented strains. At each step, the individuals with good plant and flower shape were selected. The corresponding species identification is ((*scabratriflora*)*xscabra*)*x*((*scabratriflora*)*xscabra*).

The multiple-step cross-breeding program was performed over multiple growing seasons up to 2018; in October 2018, selection of the variety was performed. We asexually reproduced the variety by vegetative reproduction through cuttings, tissue culturing via lateral bud culture, and in October 2020, the new variety was found to be stable and asexually reproduced true to type in successive generations.

2

The variety was developed and propagated in Iwate, Japan.

The variety can be propagated by cutting (optimal timing is mid-February) and/or tissue culturing via lateral bud culture.

Cultivation of the variety does not require particular conditions. Maintenance and storage method of the plant material can be by tissue culture via lateral bud culture.

10 The variety is adapted for use as cut flowers or pot flowers.

SUMMARY OF THE VARIETY

15 The variety is distinguished by the color of inner side of lobes being strong purplish blue (96C on RHS Colour Chart) and by its time of flowering in mid-October, as compared to 'Shine Blue Ashiro' variety whose color of inner side of lobes is strong blue (N95A on the RHS Colour Chart) and whose time of flowering in late September. 'Shine Blue Ashiro' is unpatented.

20 A comparison with Shine Blue Ashiro variety is presented as follows in Table 1:

TABLE 1

	Shine Blue Ashiro	Ashiro 29-2030
Color of inner side of lobes	Strong blue (N95A on the RHS Colour Chart)	strong purplish blue (96C on the RHS Colour Chart)
Time of flowering	Late September	mid-October

35 Additional distinguishing characteristics of the 'Ashiro 29-2030' plant are the five (5.0 on average) lobes of the paracorolla, and the strong purplish-blue color (96D on R.H.S. Colour Chart), with spots, of the secondary lobes with acute apex in-between the main lobes of the corolla.

BRIEF DESCRIPTION OF THE DRAWINGS

In the accompanying drawings, which are as nearly true as is reasonable possible to make in a color illustration of this type:

FIG. 1 is a color photograph showing the 'Ashiro 29-2030' plant as grown in a culturing bed;

FIG. 2 is a color photograph showing flowers of the 'Ashiro 29-2030' plant;

FIG. 3 is a color photograph showing flowering stages of flowers of the 'Ashiro 29-2030' plant;

FIG. 4 is a color photograph showing petals of flowers of the 'Ashiro 29-2030' plant;

FIG. 5 is another color photograph showing flowers of the 'Ashiro 29-2030' plant; 1

FIG. 6 is a map showing the steps of the cross-breeding program from which the variety was obtained.

Due to chemical and/or digital development, processing and printing, the plants or portions of plants depicted in the photographs may or may not be precisely accurate, when compared to the actual botanical specimens.

DETAILED DESCRIPTION OF THE INVENTION

The plants in the botanical description below and shown in the Figures were grown in Iwate, Japan. The plants were collected in October 2020 at age 16 months.

Colors are given according to The 2015 R.H.S. Colour Chart.

Botanical description:

TABLE 2

Stem	Length:	82.7 cm	55	Color of inner side of lobes:	strong purplish blue (96C on RHS Colour Chart)
	Stem shape in cross-section:	circular		Tube length (average):	31.4 mm
	Thickness (main flowering stem):	4.1 mm		Color of upper part of inner side of tube:	strong purplish blue (96C on RHS Colour Chart)
	Number of flowering stems per plant (average):	14.9	40	Color of upper part of outer side of tube:	greyish purplish red (N77D on RHS Colour Chart)
	Texture:	smooth		Streaked pattern on outer side of tube:	present
	Color:	strong yellow green (145A on RHS Colour Chart)		Color of streaked pattern on outer side of tube:	greyish purplish red (N77D on RHS Colour Chart)
	Anthocyanin coloration at two thirds from base:	present	45	Density of spots on the inner side of the corolla lobes:	sparse
	Number of internodes longer than 5 mm (average):	22.7		Density of spots on the upper part of the inner side of the corolla tube:	sparse
	Length of internode in central third:	4.0 cm		Density of spots on the outer side of the corolla tube:	absent
	Side shoots:	present		Number of lobes:	5
Leaf	Number of side shoots with only one node (average):	1.5	50	Length of lobes:	11.0 mm
	Number of side shoots with more than one node (average):	7.5		Width of lobes:	11.3 mm
	Position of longest leaf:	in lower third		Shape of lobes:	ovate
	Length:	7.8 cm		Shape of distal end of lobes:	acute
	Leaf arrangement:	opposite leaf arrangement	55	Presence of secondary lobes:	present
	Leaf attachment:	sessile		Average number of secondary lobes per flower:	5
	Leaf apex:	acuminate		Shape of secondary lobe apex:	acute
	Leaf margin:	entire		Color of secondary lobes:	strong purplish-blue (96D on RHS Colour Chart)
	Leaf base:	acute		Presence of spots on secondary lobes:	present
	Leaf texture (inner side):	smooth			
Flower	Leaf texture (outer side):	smooth	60		
	Leaf color (inner side):	strong yellow green (143A on RHS Colour Chart)			
	Leaf color (outer side):	moderate yellow green (139D on RHS Colour Chart)			
	Number of stamens:	10			
	Length of stamens:	1.5 cm			

TABLE 2-continued

Leaf venation pattern:	parallel venation (three lines)
Width:	5.0 cm
Shape:	narrow lanceolate
Shape in cross section:	folded upwards
Shape in longitudinal section:	straight
Twisting:	absent
Number of conspicuous veins:	3
Anthocyanin coloration:	absent
Distribution of flowers:	clustered
Position of flowers:	terminal and axillary
Number of terminal flowers (average):	7.5
Typical plant height:	about 82.7 cm (cut flower or potted plant)
Typical growth habit:	erect
Plant spread (average):	49.7 cm
Sequence of flowering:	from top downwards
Number of flowers at central flowering node (average):	2.9
Number of flowering node:	5.7
Shape of bud:	narrow oval
Length of bud (average):	46.01 mm
Diameter of bud (average):	9.79 mm
Color of bud:	greyish purplish red (N77D on RHS Colour

Type:	Chart)
Time of flowering:	double
Flower longevity (potted plant):	mid-October
Flower longevity (cut flower):	13 days
Depth:	7 days
Diameter at middle third:	54.5 mm
Shape:	17.7 mm
Diameter at top:	campanulate
Curvature of lobes:	32.3 mm
Color of inner side of lobes:	reflexed
Tube length (average):	strong purplish blue (96C on RHS Colour Chart)
Color of upper part of inner side of tube:	31.4 mm
Color of upper part of outer side of tube:	strong purplish blue (96C on RHS Colour Chart)
Streaked pattern on outer side of tube:	greyish purplish red (N77D on RHS Colour Chart)
Color of streaked pattern on outer side of tube:	present
Density of spots on the inner side of the corolla lobes:	greyish purplish red (N77D on RHS Colour Chart)
Density of spots on the upper part of the inner side of the corolla tube:	sparse
Density of spots on the outer side of the corolla tube:	sparse
Number of lobes:	absent
Length of lobes:	5
Width of lobes:	11.0 mm
Shape of lobes:	11.3 mm
Shape of distal end of lobes:	ovate
Presence of secondary lobes:	acute
Average number of secondary lobes per flower:	present
Shape of secondary lobe apex:	5
Color of secondary lobes:	acute
Presence of spots on secondary lobes:	strong purplish-blue (96D on RHS Colour Chart) for both surfaces present

US PP35,011 P2

5

TABLE 2-continued

Paracorolla	Presence of paracorolla:	present	
	Number of paracorolla lobes (average):	5.0	
	Paracolla apex shape:	acute	
Calyx	Anthocyanin coloration:	present	
	Length of tube:	16.7 mm	
	Diameter of tube:	6.6 mm	
	Shape of tube:	funnel-shaped	
	Shape of lobe:	narrow lanceolate	
Sepal	Sepal number:	5	
	Sepal lobe shape:	narrow lanceolate	
	Sepal apex:	acute	
	Sepal color (inner side):	strong yellow green (141D on the RHS Colour Chart)	
	Sepal color (outer side):	moderate yellow green (138B on the RHS Colour Chart)	
Reproductive organs	Stamens and anther:	stamens are mutated into petals	
	Time of flowering:	late October	
	Pistil number:	1	
	Pistil length (average):	36.0 mm	
	Anther shape:	narrow oval	

6

TABLE 2-continued

5	Anther color:	light yellow green (145D on RHS Colour Chart)
In the above chart, specific numbers correspond to average values.		
Other features of the plant are as follows:		
<i>Disease resistance.</i> —Normal resistance was observed for pests and diseases in Iwate, Japan, using pest control by chemical spraying for gentian.		
<i>Cold hardiness.</i> —Strong, the variety can withstand winter in Iwate, Japan, including low temperatures of about -10° C. with abundant snow.		
<i>Heat tolerance.</i> —Normal, the variety can withstand summer in Iwate, Japan, including high temperatures of about 35° C.		
<i>Flower fragrance.</i> —Absent.		
We claim:		
1. A new and distinct variety of <i>Gentiana</i> plant named 20 'Ashiro 29-2030', substantially as described and illustrated herein.
